BUILDING

Anthony M. Rossi, Medinah, Ill., assignor to Henry's
Drive In, Inc., a corporation of Illinois

Filed Nov. 18, 1968, Ser. No. 14,522

Term of patent 14 years

Int. Cl. D25—04

U.S. Cl. D13—1

Fig. 1

Fig. 2

Fig. 3

FIG. 1 is a perspective view of the building of my design showing the front and one side thereof;

FIG. 2 is a front elevation view of the building of my design;

FIG. 3 is a rear elevation view of the building of my design;

FIG. 4 is a side elevation view of the building of my design showing one side thereof; and

FIG. 5 is a side elevation view of the building of my design showing the other side thereof.

The dominant features of the design reside in the portions shown in full lines.

I claim:

The ornamental design for a building, as shown and described.
